UNITED STATES PATENT OFFICE.

WILEY MERRITT, OF COVINGTON, GEORGIA, ASSIGNOR TO HIMSELF AND
JOHN C. CAMP, OF SAME PLACE.

RIB FOR COTTON-GINS.

SPECIFICATION forming part of Letters Patent No. 280,498, dated July 3, 1883.
Application filed November 4, 1882. (No model.)

To all whom it may concern:

Be it known that I, WILEY MERRITT, of Covington, in the county of Newton and State of Georgia, have invented a new and useful 5 Improvement in Ribs for Cotton-Gins, of which the following is a full, clear, and exact description.

The object of the invention is to make the wearing-plate used upon cotton-gin ribs adjustable, and this I accomplish by slotting the rib, forming a lug upon the wearing-plate, and employing a screw, as hereinafter described, and pointed out in the claim.

Reference is to be had to the accompanying 15 drawings, forming a part of this specification, in which similar letters of reference indicate corresponding parts in both the figures.

Figure 1 is a perspective view of a cotton-gin rib with my improvement. Fig. 2 is a 20 perspective view of the wearing-plate detached.

The rib A is of ordinary form, and at its upper side, and at the place where the saw-teeth pass between the ribs, is the wearing-plate B, the same being a crescent-shaped piece 25 of metal fitting snugly upon the face of the rib, and attached thereto by a screw, a. The rib is formed with a slot, b, and the wearing-plate B is formed with a lug, c, entering the slot, 30 and the screw a passes through the slot from

the under side of the rib and enters the lug. This construction allows adjustment of the wearing-plate B up or down upon the rib according to the wear. The wearing-plate can readily be removed when it becomes worn to such an extent as to allow the seeds to pass through with the lint and a new plate put in place without removing the ribs from the gin, thus saving the expense of a new set of ribs whenever they become worn so as to be unfit for use. The plates may be applied to a set of ribs that have already become so notched and worn as to allow the seeds and motes to pass through with the lint, and when applied in the manner shown the wearing-plate renders the ribs as good as new. When applied to a new set of ribs, the wear will be entirely upon the plates, which can be removed from time to time, as required.

Having thus described my invention, I claim as new and desire to secure by Letters Patent-

The plate B, formed with the lug c and the attaching-screw a, in combination with the rib A, having the slot b, substantially as shown and described.

WILEY MERRITT.
